UNITED STATES PATENT OFFICE

133,580

DESIGN FOR A COMBINED ASH TRAY AND CIGARETTE AND CIGAR HOLDER AND EX- TINGUISHER

Jacob I. Robin, New York, N. Y.

Application January 30, 1942, Serial No. 105,522

Term of patent 3½ years

To all whom it may concern:

Be it known that I, Jacob I. Robin, a citizen of the United States, residing at Manhattan, in the county of New York, city and State of New York, have invented a new, original, and ornamental Design for a Combined Ash Tray and Cigarette and Cigar Holder and Extinguisher, of which the following is a specification, reference being had to the accompanying drawing, forming part thereof.

Fig. 1 is a top plan view of a combined ash tray and cigarette and cigar holder and extinguisher, showing new design, and

Fig. 2 is a cross section on the line 2—2 of Fig. 1;

Fig. 3 is the bottom view of the cigarette and cigar holder and extinguisher, alone.

I claim:

The ornamental design for a combined ash tray and cigarette and cigar holder and extinguisher, substantially as shown and described.

JACOB I. ROBIN.
